Louis F. JULIEN

Charles E. Wilson

ATTORNEY.

UNITED STATES PATENT OFFICE

LOUIS F. JULIEN, OF DETROIT, MICHIGAN, ASSIGNOR TO CHAMBERLIN METAL WEATHERSTRIP COMPANY, OF DETROIT, MICHIGAN, A CORPORATION OF MICHIGAN

WEATHER STRIPPING

Application filed May 9, 1929. Serial No. 361,585.

This invention relates to weather stripping for sliding window sash, the purpose being to provide weather stripping that is mounted upon the sash and in engagement with the frame in which the sash is slidable in a manner to make a weather tight joint. The practice heretofore has generally been to provide weather strip upon the window frame which requires considerable hand labor in fitting the sash to the frame in cooperative relationship with the weather strip.

This invention has for its object to practically completely obviate the hand labor involved in weather stripping a window and provides a unique form of strip whereby the strip is carried by the sash and has a flexible portion extending outwardly from the sash to engage the sash runway of the window frame. By this arrangement the sash is flexibly held in a central position between the two vertical side members of the frame and therefore the sash is less liable to bind as even a greater interstice may be provided than usual if desired without affecting the weather-proof effect secured by the use of the strip.

A further object of the invention is to provide in combination with a sash having oppositely disposed grooves on the side and edge of the sash into which portions of the strip engage under spring tension avoiding necessity of nailing the strip to place inasmuch as when once assembled with the sash and positioned in the frame the strip is automatically retained in place.

A further feature of the invention is to provide a strip that is adaptable for use upon both the top and bottom as well as the vertical sides of the sliding sash whereby, when the sash is in closed position, the interstice between the upper and lower sash at the meeting rail, the interstice between the lower rail and frame and the top rail and frame are weather-proofed as well as the interstice between the side members and the sash groove of the frame.

A feature of this invention resides in the construction of the strip which has a portion thereof bent for insertion in a groove provided in one member of a pair and a

part extending outwardly of the groove at an angle to the face of the member for engagement with the other member closing thereagainst whereby the interstice between the members is sealed, and it is further a feature of the invention to provide such a strip with the longitudinal edge of the angular portion inturned toward the face of the grooved member.

These and other objects and the various novel characteristics of the construction whereby these several objects may be accomplished is shown in preferred form in the accompanying drawings in which—

Fig. 1 is an elevation of a window having the upper and lower sliding sash mounted in the frame.

Fig. 2 is an enlarged section taken on line 2—2 of Fig. 1.

Fig. 3 is an enlarged section taken through the meeting rails on line 3—3 of Fig. 1.

Fig. 4 is a perspective view of a cross section of the weather strip in its preferred form.

Fig. 5 is a perspective view illustrating the construction of the strip applied to a cross member and a side member of the sash.

Fig. 6 is a perspective view showing the end of the cross strip as constructed at this meeting point with the vertical strip.

Fig. 7 is a perspective view of the end of the vertical strip for cooperative relation with the end of the cross strip shown in Fig. 6.

In its preferred form the strip is of metal spring like in character and consists of the side flange or wing 1 and a similar flange portion 2 normally at an angle one to the other of less than ninety degrees. The flange 1 terminates in an inbent end portion 3 having the terminal edge 4 thereof bent back upon itself to form a smooth edge portion. The flange 2 has the wing member 5 preferably integrally formed therewith by an inbent part 6 and an outbent part 7 to form a rounded edge 8 corresponding somewhat to the edge of the portion 3 of the flange 1. This rounded edge 8 is thus formed by spaced walls 6 and 7 and when this

portion of the strip is inserted in a groove in a sash rail or other character of grooved member as hereinafter described, it is held therein under spring pressure due to the 5 walls 6 and 7 being pressed together slightly in entering the groove. The flexible wing portion 5 has a portion 9 adjacent its edge turned inwardly slightly from the plane of the portion 5 with its terminal edge portion 10 turned back upon itself to form an outward rounded edge for this flexible strip. The sash frame has the vertical and cross members grooved to receive the weather strip. As shown in Fig. 2 the vertical member 11 has a groove 12 formed in the edge of the sash riding in the sash groove 13 of the window frame 14 which is formed between the usual parting strip 15 between the upper and lower sash 11 and 16 and the 15 outer mold or strip 17 while the inner sash 16 has an edge portion riding in the sash groove 18 formed between the parting strip 15 and the mold 19. This sash bar 11 also has a groove 20 in the side face of the sash 20 adjacent the parting strip. These two grooves 12 and 20 are formed in the adjacent faces of a rectangular portion of the frame and provide recesses for the lip or edge 3 and the edge portion 8 respectively of 25 the strip to engage.

As the flanges 1 and 2 to which the edge portions are respectively connected are normally less than ninety degrees apart, to position the same on the sash requires the 30 spreading of these two flanges apart to a ninety degree angle and, as this strip is formed of sufficiently resilient metal, the strip automatically clamps in position in the respective grooves and with the flexible 35 wing or flange 5 lying in contact with the bottom of the sash groove 13 or other portion of the window frame. This relationship of parts illustrates the reason for turning the edge portion 9 of the part 5 slightly inwardly toward the flange 2 as it prevents any 40 rough or cut edge of the flange from gouging into the window frame. It is also to be noted that this flange portion 5 does not extend to the point of connection of the flange 2 with the flange 1 and thus is spaced 45 from the parting strip shown in Fig. 2 and therefore not in position to gouge into the same. The upper sash is shown in section in Fig. 2 while the lower sash meeting rail is 50 shown in elevation. It will be noted in this view that the strip for the vertical side of the lower sash 16 is positioned in a reverse relation to that shown in the vertical side member 11—that is, the flexible wing portion 5 and 5^a are both turned toward the parting strip and thus are reversely positioned. There is a strip for each vertical side member of each sash, a strip for the 55 meeting rail of the top sash and a strip for 60

the top member of the upper sash and for the bottom member of the lower sash.

There is no necessity to provide a strip on the meeting rail 21 of the lower sash as will be observed from Fig. 3. The meeting rail 21 for the lower sash is outwardly inclined 70 on the meeting side as indicated at 22 while that of the upper sash is correspondingly inclined as indicated at 23 and a weather strip is provided at the lower and inner edge of this meeting rail 24 of the upper sash, it having the flexible flange 5^b contacting the inclined face 22 of the lower sash when in closed position. This rail 24 is provided with grooves 12^a and 20^a, corresponding to the grooves 12 and 20 in the vertical rail 11, into which the respective edge portions of the strip clamp as before described. As the flexible strip 5^a extends downwardly, the lower sash may be readily raised away from the strip and when brought to closed position comes properly into contact with the strip which, when the sash is separated, springs outwardly from the inclined face 23 of the meeting rail 24 of the upper sash. This strip introduced between the meeting rails not only closes the interstice therebetween but due to the spring like character of the flexible strip 5 tends to separate the two rails and to hold 85 the sash more or less tightly in engagement with the opposed sides of the respective sash grooves and thus naturally prevents rattling of these parts. This flexible strip on the side rails of either of the sash tends to centralize the sash between the two side grooves provided therefor in the frame member and thus reduces frictional contact of the sash edge with its groove making the window much easier to raise or lower.

100 This is not only due to the lessened friction but also to the fact that the sash is sustained in its relative spaced relation with the sash groove throughout its length thus tending to cause the sash even when lifted from one side to move freely without tilting or cramping.

105 In the perspective view Fig. 5, the upper cross member 25 of the upper sash is shown in conjunction with the vertical member 11 to illustrate the construction of the strip for these respective sash rails at the meeting rails at the meeting point. The strip 26 extending across the upper rail 25 has its flange 27 and inturned edge portion 28 cut away at the end as is indicated at 29 and the strip on the vertical sash element 11 has its end 30 bent back at an angle shortening the flange 3 which, when the parts are assembled as shown in Fig. 5, just meets the end 31 of the flange 28 of the strip 26 on the top rail 25 with the angular portion of the flange 1 overlying the portion 32 at the end of the strip 26. The relative relationship of these parts will be understood 110

from the disassembled but relatively positioned parts in Figs. 6 or 7 and the assembled relation in Fig. 5.

When these strips are mounted in the respective sash grooves provided for the same and the sash mounted in the window frame there is no possibility of displacement of the respective strips but a flange of either of the strips may be tacked in place if desired. This is usually unnecessary as it will be seen from Fig. 5 that the strip across the upper sash may not move endwise nor may the strip for the vertical rail 11, due to the fact that the flanges 3 and 28 practically meet in the grooves of the respective rails provided therefor.

It is to be noted, however, that the strip shown in section in Fig. 3 and indicated generally at 40 terminates slightly short of the 20 parting strip on opposite sides of the window frame. This is indicated in dotted lines in Fig. 2 and when the sash is assembled in the frame the strip may not move out of position as it would engage the parting strips. In order to avoid cutting of the 25 parting strip the ends of this weather strip 40 adjacent each parting strip of the frame may be inturned to prevent a cutting edge coming in contact with the strips. The remaining strips which join at the corners of 30 the sash as indicated in Fig. 5 are practically held from displacement one by the other.

By the general arrangement of the strip described, it having the spring clamping action and the flexible contact strip, a very inexpensive weather strip is provided requiring no hand labor in the fitting of the sash to the strip as the grooves for the strip may 35 be formed by a rabbeting machine at the time the sash is manufactured and all that is necessary for the workmen to do in assembling the sash in the frame is to cut the strip of the necessary length or it may be 40 provided in standard lengths for standard sizes of windows.

It is further to be understood that the strip, herein described as being applied to the outer face of a sash to engage a frame in 45 which the sash is slidable, may also be applied or utilized in any appropriate structure where a space between two opposing members is to be closed irrespective as to whether or not the said members are in 55 sliding relationship longitudinally of the strip.

Having thus described my invention, its utility and mode of operation, what I claim and desire to secure by Letters Patent of 60 the United States is—

1. A metal weather strip for sliding window sash, comprising the combination with a sash having its rail provided with a groove in its outer side face respectively, of a metal 65 weather stripping having a body provided

with portions adapted to engage the grooves under spring pressure, and a resilient weather closing portion attached to the body and extending inwardly from the outer face of the sash. 70

2. A metal weather stripping for sliding window sash and frame having a groove therefor, comprising the combination with a sash having its rail provided with grooves, of a metal weather stripping having a body provided with portions to engage the grooves under spring pressure, and a resilient portion attached to the body providing a weather closing portion between the sash 75 and the frame. 80

3. The combination with a window frame and a sash slidable therein, of a spring metal strip having a body formed of two portions lying at an angle one to the other and provided with indent portions, said sash having a groove in its edge and in its side face to receive the said indent portions, and a resilient weather closing portion attached to that portion of the body engaging the sash edge, the normal angle between the said two body 85 portions being less than the angle between the edge and face of the sash whereby the strip is secured to the sash under spring pressure. 90

4. The combination with a window frame and a pair of sash slidable therein, the frame having grooves for the respective sash and the sash each having oppositely disposed side rails, a cross member at the respective opposite ends and a meeting rail at the other end, of a spring metal weather strip consisting of a body member secured to the side rails and bottom cross member of the lower sash and a similar strip secured about the side rails and cross member of the other sash, the said strips on the respective sash being joined together at their meeting ends, each side rail and cross member portion of the strips of the respective sash having a resilient portion extending at an angle thereto 100 for engagement with the frame, and a similar strip on the meeting rail of one sash having an outwardly inclined weather closing portion engaging the meeting rail of the other sash when in closed position. 105 110

5. A metal weather strip for a sash slidable in a frame provided with grooves therefor, comprising a body portion detachably secured to the side rails and a cross member of the sash, the said body portion on the side rails being attached to the portion on the cross member, and an outwardly inclined weather closing portion integral with the body member of the respective side rails and cross member and adapted to engage 115 the bottom of the frame grooves for the sash. 120

6. A metal strip for closing an interstice between opposing faces of two complementary members one of which is provided with a 130

longitudinal groove in its face at a distance from one edge, comprising a sheet of flexible metal having a part thereof shaped to engage in the groove of the one member and 5 an integral part extending therefrom at an angle to the face and towards said edge of the grooved member to be deflected toward the said face by engagement with the other member, said integral angularly positioned 10 part terminating short of said edge of the grooved member and having its edge portion inturned toward the face of the grooved member.

7. A metal strip for closing the interstice 15 between the opposing faces of two complementary members one of which is provided with a longitudinal groove in its face at a distance from one edge, comprising a sheet of metal having a portion thereof folded to 20 form a portion engaging in the groove and a portion extending outwardly therefrom terminating short of said edge and lying at an angle to the face of the grooved member for deflection toward the face of said 25 grooved member by engagement with the said companion member.

8. A metal strip for closing an interstice between opposing faces of two complementary members one of which is provided with a 30 groove, comprising a sheet of flexible or resilient metal having a portion thereof shaped to provide a flexible portion for frictional engagement in the groove of said grooved member, and an integral part extending outwardly of the groove and arranged for yieldable engagement with the other member.

In testimony whereof, I sign this specification.

40 LOUIS F. JULIEN.
